UNITED STATES PATENT OFFICE.

DOROTHY N. STEWART AND JOHN L. WILLIAMS, OF PHILADELPHIA, PENNSYLVANIA,
ASSIGNORS TO ACADEMY CLUB TOY MAKING, OF PHILADELPHIA, PENNSYLVANIA,
A COPARTNERSHIP CONSISTING OF DOROTHY N. STEWART AND OTEY WILLIAMS.

MECHANICAL TOY.

1,407,825.

Specification of Letters Patent. Patented Feb. 28, 1922.

Application filed February 6, 1920. Serial No. 356,662.

To all whom it may concern:

Be it known that we, DOROTHY N. STEWART, a citizen of the United States, and a resident of the city of Philadelphia, county 5 of Philadelphia, and State of Pennsylvania, and JOHN L. WILLIAMS, a citizen of the United States, and a resident of the city of Philadelphia, county of Philadelphia, and State of Pennsylvania, have invented an Improvement in Mechanical Toys, of which the 10 following is a specification.

The present invention relates to an improvement in mechanical toys, one object being to provide a plunger mechanism whereby 15 an independent portion of the toy may be forcibly ejected from a recess therein by means which may readily be adapted to the toy makers' art.

One embodiment of our invention is illustrated in the drawing accompanying the present specification, the single figure of which is a longitudinal vertical section through a toy shaped to simulate a miniature whale.

In the particular embodiment of the invention illustrated in the drawing, one object has been to reproduce a mechanical representation of a portion of the story of Jonah and the whale, although it is obvious that the mechanism may readily be adapted 25 to other uses. As shown in the drawing, a device embodying our invention may include a body portion 1 having a recess 2 intersecting a recess 3 at any desired position. A plunger 4 may be mounted in the recess 3, the function of said plunger being to strike 30 a projectile 5 or other similar independent member to forcibly eject the same from the open end of the recess 3. A coiled spring 6 may be interposed between the closed end of 35 the recess 3 and the bottom of the plunger 4, said spring being normally held under compression when the plunger is in retracted position. The plunger 4 may be provided 40 with a longitudinally extending slot 7, the 45 sides of which are adapted to embrace a fixed 50 detent 8 which is arranged transversely across the recess and acts as a stop to limit the forward movement of the plunger 4 when the same is actuated by expansion of 55 the spring 6.

Suitable plunger locking and releasing mechanism may include a yielding detent 9, here shown as a perforated plunger having a transverse opening 10 extending dia-

metrically through said plunger. A coiled 55 spring 11 interposed between the bottom of the recess 2 and the base of the plunger or detent 9 operates to hold said detent in the path of plunger 4 so that the latter will press 60 yieldingly against a portion of said detent. The passageway 10 through the detent 9 is preferably of suitable size and shape to permit the plunger 4 to move therethrough without obstruction. The member 5 will 65 also be of suitable size and shape to fit into the passageway 10. In the form of device illustrated in the drawing, the projectile 5 may be a hollow member enclosing a relatively heavy ball 12, free to move from end to end 70 of the projectile.

In operation, the apparatus thus far described may be set for use by inserting the projectile 5 into recess 3 and through the passageway 10 of the plunger 9, pressing 75 said projectile against the forward end of the plunger 4, thus forcing said plunger back into the recess 3 and permitting the plunger 9 to move forward in the recess 2 to such a position that the plunger 9 will be interposed in the path of the plunger 4 to 80 lock the same in retracted position, at the same time holding the spring 6 under compression. By depressing the exposed end of plunger 9 against the pressure of spring 11, the plunger 9 may be moved sufficiently to release plunger 4 so that the latter will be 85 thrust forcibly into the passageway 10 and will strike the projectile 5 in such a way as to eject the same from the open end of the recess 3, which end in the illustrated embodiment of the invention may be made to simulate the mouth of a whale.

If desired, the form of toy representing a whale or great fish may be weighted at its posterior end in such a manner as to retain 95 the forward end normally in elevated position when the toy is lying on the ground or on the floor. For this purpose, we show a relatively heavy portion 13 positioned in such a manner that the center of gravity of the complete toy will be located relatively toward the rear. When the weighted construction is used, it is contemplated that the release of the projectile or the "Jonah" may be accomplished by pressing down the head 100 of the toy against the ground or the floor and then quickly removing the manual pressure. Thus, the head of the whale or great 105

fish will rear up and oscillate after the expulsion of the projectile.

We claim as our invention:

1. In a toy, the combination of a body portion having intersecting recesses, a striking plunger arranged in one of said recesses, a spring operatively engaging one end of said plunger and normally held under compression and a locking plunger arranged in the other recess and normally spring pressed to retain the striking plunger in retracted position, said locking plunger having a transverse passageway positioned to register with the striking plunger recess when the locking plunger is moved to releasing position and to permit spring actuated movement of the striking plunger therein.
2. In a toy, the combination of a body portion having intersecting recesses, a striking plunger arranged in one of said recesses, a spring operatively engaging one end of said plunger and normally held under compression, a locking plunger arranged in the other recess and normally spring pressed to retain the striking plunger in retracted position, and means for limiting the striking movement of the striking plunger when the locking plunger is moved out of its normal retaining position.
3. In a toy, the combination of a body portion having intersecting recesses, a spring pressed plunger arranged in one of said recesses, a yielding detent arranged in the other recess and normally holding said plunger in spring compressing position, said detent having one end exposed outside of the body portion and a passageway intermediate its ends and adapted to register

with said plunger to permit the passage thereof when the detent is moved inwardly.

4. In a toy, the combination of a body portion having intersecting recesses, a spring pressed plunger arranged in one of said recesses, said plunger having a longitudinal slot, a fixed detent arranged transversely of the recess and positioned to engage said slot, a yielding detent positioned in the other recess and normally in the path of the plunger, said detent being movable out of said path to release the plunger.

5. In a toy, the combination of a recessed body member having a bottom surface of longitudinally curved cross sectional contour, the crest of said curved surface forming a fulcrum normally positioned rearwardly of the center of gravity of the body, a projectile adapted to be placed in the recess of the body member to shift the center of gravity to a position forwardly of the fulcrum, and means for ejecting said projectile from the recess in the body member.

6. In a toy, the combination of a body portion having intersecting recesses, a spring pressed striking plunger in one of said recesses, a spring pressed locking plunger in the other recess having a passageway and manually operated means extending through said passageway to move the striking plunger longitudinally while permitting longitudinal movement of the locking plunger into locking position.

In testimony whereof, we have signed our names to this specification.

DOROTHY N. STEWART.
JOHN L. WILLIAMS.

Certificate of Correction.

It is hereby certified that the assignee in Letters Patent No. 1,407,825, granted February 28, 1922, upon the application of Dorothy N. Stewart and John L. Williams, of Philadelphia, Pennsylvania, for an improvement in "Mechanical Toys," was erroneously described and specified as "Academy Club Toy Making, of Philadelphia, Pennsylvania, a copartnership consisting of Dorothy N. Stewart and Otey Williams," whereas said assignee should have been described and specified as *Dorothy N. Stewart and Otey Williams, co-partners doing business as Academy Club Toy Makers, of Philadelphia, Pennsylvania*, as shown by the records of assignments in this office; and that the said Letters Patent should be read with this correction therein that the same may conform to the record of the case in the Patent Office.

Signed and sealed this 28th day of March, A. D., 1922.

[SEAL.]

KARL FENNING,
Acting Commissioner of Patents.
